3,316,588 PLIABLE MOLDING TOOL

Steve Vezirakis, Vancouver, Wash., assignor to Don's Sports Systems, Inc., a corporation of Washington
Filed Nov. 9, 1964, Ser. No. 409,771
2 Claims. (Cl. 18—5.1)

This invention relates to improvements in bowling balls and more particularly relates to an improved bowling ball and method and apparatus for forming the finger holes in bowling balls.

Bowling balls have heretofore been drilled to form finger grips for the ball, the finger holes being sized and spaced to receive the thumb, middle finger and ring finger of the bowler and to comfortably fit the spread of the bowler's fingers.

The balls many times are not drilled for the hand of a particular bowler and where the bowler does not have his own ball, he will select a ball in which the hole size and spread approximates the hand of the bowler.

Even where the ball is drilled to the hand of the bowler, it is difficult to obtain an exact fit and the finger holes are frequently too tight or too loose and the walls of the finger holes are cylindrical throughout their length and do not provide sufficient gripping surface to give the average bowler the required control of the ball.

It is, accordingly, the principal object of the present invention to remedy the foregoing deficiencies by providing a new and improved form of bowling ball in which the finger holes are formed to generally conform to the fingers of the bowler, to increase the finger gripping action on the ball with the resultant added comfort to the bowler and increased control of the ball.

A further object of the invention is to provide an improved form of bowling ball having molded finger holes in the ball forming permanent finger holes conforming to the fingers of the bowler.

A further object of the invention is to improve upon the bowling balls heretofore in use by molding finger inserts in the ball to form an integral part of the ball and by so molding the inserts as to generally conform to the forms of the fingers holding the ball, to increase the gripping action and control of the ball and accommodate the ball to move smoothly off the fingers in the act of throwing the ball.

A further object of the invention is to provide a tool or pattern for forming the finger grip inserts molded in bowling balls and made from a pliable material accommodating ready removal of the insert from the solid mold, by the pulling on and contraction of the insert.

Still another object of the invention is to provide an improved method for forming the finger holes in bowling balls to size, in which the finger holes are molded in the balls by a compound different from the material from which the ball is made and forming permanent finger inserts in the balls generally conforming to the fingers of the bowler.

These and other objects of the invention will appear from time to time as the following specification proceeds and with reference to the accompanying drawings wherein:

FIGURE 1 is a generally diagrammatic view of a bowling ball;

FIGURE 2 is a view in side elevation of a molding tool or pattern constructed in accordance with the principles of the present invention for forming the finger holes in the bowling ball;

FIGURE 3 is a view of the pattern shown in FIGURE 2 with the pattern turned 90° in a clockwise direction from the position shown in FIGURE 2, in order to show certain finger conformations of the pattern not shown in FIGURE 2;

2

FIGURE 4 is a fragmentary sectional view taken through the thumb hole of a bowling ball with molding compound in the thumb hole, and illustrating a step in the molding of the thumb hole in the bowling ball;

FIGURE 5 is a fragmentary sectional view somewhat similar to FIGURE 4 but showing the pattern in position in the thumb hole of the bowling ball and displacing the molding compound upwardly into the hole; and

FIGURE 6 is a fragmentary sectional view taken through the thumb hole of a bowling ball with the molding compound hardened and the mold removed.

In the embodiment of the invention illustrated in the drawings, I have shown in FIGURES 2 and 3 a molding tool or pattern 10 having a generally cylindrical head 11 adapted to be positioned outside of the periphery of the ball, when molding an insert therein and to form a gripping surface to accommodate withdrawal of the pattern from the mold. The pattern 10 is made from a flexible material to stretch or contract and reduce the cross-sectional area thereof upon the exertion of a pulling force thereon, to accommodate removal of the pattern from the mold. The pattern may be made from rubber, vinyl rubber, plastics, rubber-like epoxys, urethane resins, elastomeric plastics, silicone rubber and like flexible materials. A material which has been found to be satisfactory for the pattern is known to the trade as RTV silicone rubber. This will withstand the temperatures and pressures of molding and accommodate ready contraction and withdrawing of the pattern from the mold, when hardened.

The pattern 10 has a reduced diameter stem or finger portion 12 extending therefrom and formed generally to the contour of the finger, but longer than the average finger, so one pattern of a selected diameter may be used for many different lengths of fingers.

The stem 12 has a generally cylindrical wall portion 13 extending for substantially the length thereof and having an inwardly tapered flattened end portion 15, converging toward the center of the stem. The opposite side of the stem 12 from the tapered portion 15 has a recessed portion 16 generally conforming to the finger and flat in transverse section and of an arcuate form in side elevation. The recessed portion 16 terminates into a ridge 17, shown as having an outer surface of substantially the diameter of the cylindrical portion 13. The ridge 17 in turn terminates into an inwardly curved transversely flattened converging portion 19, shown as being generally arcuate in form, of the general form of the end of the finger, and meeting the tapered portion 15 in a generally uniformly curved end portion 20 to one side of the center of the pattern as shown in FIGURE 2. The portions 15 and 19, therefore, generally simulate the nail and portion of the thumb behind the nail.

The particular tool or pattern 10 herein shown is for the thumb. The patterns for the middle and ring fingers may be similarly formed, although longer and smaller in diameter than the pattern for the thumb. A large range of pattern sizes for the thumbs and fingers may be stocked to provide the required finger patterns for an individual bowler, although the patterns may be made to order if desired.

In FIGURE 1, I have diagrammatically shown a bowling ball 21 having a thumb hole 22 and finger holes 23, 23. The thumb and finger holes are drilled in a drill press by setting the ball in a fixture and arranging the ball for drilling the holes to a required pitch, as determined by a gauge for the fixture and drill press (not shown). Where the gauge may be set to zero for drilling of a thumb hole, the hole will be a radial hole and its center will intersect the center of the ball. The finger holes are usually drilled with a forward pitch, a $\frac{3}{8}$ inch forward pitch being a standard angle. With such a pitch the centers

of the finger holes intersect radial lines at distances of $\frac{3}{8}$ inch from the center of the ball.

It is, of course, understood that the pitches of the thumb and finger holes may be reverse pitches as well as a forward pitch and may even be side pitches, in accordance with the size and shape of the bowler's hand.

In forming a thumb hole, as shown in FIGURES 4, 5 and 6, the diameter of the thumb of the bowler is measured one size larger than the thumb knuckle to provide a comfortably loose fit of the thumb in the thumb hole. The measure of the length of the thumb of the bowler is also taken and the angle of the bowler's release point is determined by having the bowler grip a ball having a thumb hole 22 and finger holes 23, 23 drilled oversize, and slowly drawing the bowler's thumb out of the thumb hole. This will accurately determine the release of the bowler's thumb. Two parallel lines 25 conforming to the angle of release are then drawn on the surface of the ball as a visual guide to determine the angle at which the pattern is to be inserted.

In drilling the ball to accommodate the molding of the thumb hole therein, the ball is set up on a drill press and fixture and properly pitched in the fixture, a drill bit is then selected larger than the size of the hole to be molded. The drill bit may be $\frac{3}{32}$ of an inch larger than the largest diameter portion of the hole to allow the molding compound to settle and form a solid mold. Upon drilling of the hole 26, the top part of the ball is drilled at the pitch of the hole 26, to form a large diameter hole 27 extending along the hole 26 coaxial with the center thereof for substantially $\frac{3}{4}$ of an inch. All round edges and bevels are then cleaned from the hole to provide sharp edges throughout the hole and all dirt and material in the hole is cleaned out. The surface of the ball around the hole just drilled is also cleaned of dirt. A plugging clay 29 may then be placed around the hole to prevent the molding compound from running over the outer surface of the ball.

The hole 26 may then be filled about one-half full of a plugging compound which may be a thermosetting plastic which will rigidly harden over a period of time. One suitable material being an epoxy compound which rigidifies upon setting and is known to the bowling ball repair trade as "Ball Plug." Another compound found to be suitable and commonly used in the bowling trade is a compound known to the trade as "Ball Mate." Where this compound is used, two parts of "Ball Mate" compound should be combined with one part "Ball Mate" hardener and mixed to insure uniform blending and then allowed to stand to eliminate all air bubbles in the compound. This compound must be used within one hour from mixing.

Assuming the ball is properly drilled and the plugging clay 29 is placed along the hole on the surface of the ball, a selected plastic plugging compound in a liquid state may then be poured into the hole filling the hole substantially half full, as indicated by reference character 30, in FIGURE 4.

A finger cot 31 generally conforming to the pattern is then placed over the pattern and along the head 11 for a portion of the length thereof, to protect the pattern and facilitate the removal of the pattern when the compound hardens. The finger cot may be made from a thin plastic material generally conforming to the form of the pattern which will easily release the pattern when the compound is hardened. Any part of the finger cot sticking to the mold may readily be removed by long-nosed pliers and the like.

A finger cot being in place on the pattern, a mark 32 is made on the outside of the finger cot in accordance with the length of the finger or thumb to gauge the depth at which the pattern is set into the hole.

The finger cot being in position on the pattern, the pattern and finger cot are then inserted in the hole 26 at the proper angle determined by the thumb release lines 25—

10 25. This will displace the molding compound to surround the pattern and finger cot as shown in FIGURE 5. Where the molding compound is insufficient to come up to position slightly over the top of the enlarged diameter portion of hole 27 as shown in FIGURE 5, additional compound may be poured into the hole with the pattern 10 held in place. The pattern being positioned in the correct angular relation with respect to the ball, molding clay may be placed on the surface of the ball around the clay 29 and engaged with the head of the pattern to steady the pattern during hardening of the compound, as indicated by reference character 33.

15 The hole being completely filled with compound and the pattern being held in place by the molding clay 33, the compound should now be allowed to dry. The drying period for the compounds mentioned herein is approximately 12 hours and the temperature of drying should not be under 65° F.

20 When the compound has hardened, the head 11 of the pattern may be gripped by the hand and an outward pull on the pattern may be exerted. This will effect contraction or stretching of the pattern and this stretching along with the finger cot covering the pattern in the hardened compound, will accommodate the pattern to be readily released with a gentle pull. Any portion of the finger cot 25 not coming out with the pattern may then be removed.

25 The clay 29 and 33 may then be removed and any excess portion of the plugging compound may be trimmed to provide an outer surface flush with the peripheral surface of the ball.

30 A bevel may then be filed on the palm side of the thumb hole and the beveled part of the hole may be sanded and buffed to provide a finish like the finish on the periphery of the bowling ball.

35 It may be seen from the foregoing that I have provided a new and improved form of bowling ball having finger holes generally conforming to the thumb, index finger and ring finger of the bowler, which are formed by pouring a plastic liquid into an oversize hole and by molding the compound by a pattern generally conforming to the form of the finger of the bowler and held at a selected angle with respect to the center of the ball, depending upon the hand of the bowler.

40 The ball may thus have finger holes formed as a part 45 thereof accurately conforming to the fingers and span of the hand of the bowler and so formed as to facilitate the release of the ball and increase the comfort and ability of the bowler to control the path of the ball.

45 It may further be seen that the finger holes form an integral part of the ball and the molding compound cannot be distinguished from the material from which the ball 50 is made upon proper finish of the ball.

55 While I have herein shown and described one form in which the invention may be embodied, it may readily be understood that various modifications and variations in the invention may be attained without departing from the spirit and scope of the novel concepts thereof.

I claim as my invention:

1. A tool for forming finger holes in bowling balls conforming to the finger of the bowler comprising:
a solid pliable pattern for forming finger holes in a bowling ball adapted to fit in a predrilled oversize finger hole in the bowling ball and form a pattern for molding compound in the oversize hole, said pattern having
a generally cylindrical head on the outer end thereof,
a reduced diameter generally cylindrical wall portion extending from said head for a portion of the length of said pattern and having
a shallow flat concave recess on one side thereof for locking the pattern to the mold upon hardening of the molding compound,
a ridge at the inner end of said recess, and
converting into a flattened inwardly curved

convex portion in the general form of the end of the finger behind the nail, said cylindrical wall portion having an opposite flattened portion generally simulating the nail portion of the thumb, and said head forming a hand grip adapted to be gripped by the hand to stretch and unlock the pattern for removal from its mold.

2. The structure of claim 1, wherein the pattern is made from silicone rubber.
